UNITED STATES PATENT OFFICE.

HENRY B. MORRIS, OF MICHIGAN CITY, INDIANA.

DESIGN FOR CANE FABRIC.

SPECIFICATION forming part of Design No. 26,874, dated April 6, 1897.

Application filed February 18, 1897. Serial No. 624,053. Term of patent 7 years.

To all whom it may concern:

Be it known that I, HENRY B. MORRIS, a citizen of the United States, residing in Michigan City, in the county of La Porte and State of Indiana, have invented and produced a new and original Design for Cane Fabrics, of which the following is a specification, and which is illustrated in the accompanying drawing, showing a face view of a small piece of fabric with my design applied.

Cane fabric containing my design has relatively-narrow close-woven stripes A, alternating with a series of relatively-wide open-mesh stripes B. Each stripe A is made up of a series of parallel strips *a*, arranged close together and divided up into short lengths *a'* by a series of cross-strips *a²*. Each stripe B has a series of pairs of strips *b*, forming continuations of the strips *a²*, and these are crossed by diagonally-arranged strips *b'*, which, with the strips *b* and the strips *b²*, run-

ning parallel with the stripes A, produce between each pair of stripes two rows of hexagonal figures *c*.

The leading feature of my design is the alternately-arranged narrow close-woven and relatively-wide open-mesh stripes, the former being made up of parallel strips arranged close together and divided up into short sections by cross-strips and the latter containing strips arranged at right angles to each other and crossed by diagonal strips, producing a series of rows of hexagonal figures *c*.

I claim—

The design for cane fabric substantially as herein shown and described.

In testimony whereof I have hereunto subscribed my name.

HENRY B. MORRIS.
